DAVID L. SUMMEY, OF WATERBURY, CONNECTICUT, ASSIGNOR TO CHASE ROLLING MILL CO., OF WATERBURY, CONNECTICUT, A CORPORATION.

EXTRUSION-MACHINE.

1,109,555.

Specification of Letters Patent.

Patented Sept. 1, 1914.

Application filed January 4, 1913. Serial No. 740,133.

To all whom it may concern:

Be it known that I, DAVID L. SUMMEY, a citizen of the United States, residing at Waterbury, in the county of New Haven and State of Connecticut, have invented a new and useful Improvement in Extrusion-Machines; and I do hereby declare the following, when taken in connection with the accompanying drawings and the characters 10 of reference marked thereon, to be a full, clear, and exact description of the same, and which said drawings constitute part of this application, and represent, in—

Figure 1 a plan view of an extrusion-machine constructed in accordance with my invention. Fig. 2 a view thereof in front elevation. Fig. 3 a view thereof in left hand end elevation. Fig. 4 a broken view of the machine in central horizontal section, 15 on a larger scale than Fig. 1, with the left-hand extrusion cylinder and the mandrel-operating cylinder broken away, and showing the sectional container in its assembled position. Fig. 5 a broken view in central, 20 horizontal section, of the center of the machine, showing the sectional container in its disassembled position. Fig. 6 a broken view in vertical central section on the line *a—b* of Fig. 1, showing the sectional container in its assembled position, and the right-hand extrusion cylinder the pivotal right-hand 25 ram of which is shown in its retired or billet-feeding position by broken lines. Fig. 30 7 a broken view in vertical central section on the line *c—d* of Fig. 1, showing the mandrel-carrying and die-carrying sections of the 35 sectional container in their assembled positions. Fig. 8 a broken view on the line *e—f* of Fig. 1, looking from left to right toward 40 the left hand billet-receiving section of the sectional container and toward the left hand cross-head in which the said container section is carried. Fig. 9 a corresponding view showing the several sections of the container in their open or retired positions. Fig. 10 a view in vertical section on the line *g—h* of Fig. 1, showing the several sections 45 of the sectional container in their assembled or closed positions. Fig. 11 a corresponding 50 view showing the several sections of the sectional container in their disassembled or open positions. Fig. 12 a plan view of one form of single billet that I may extrude in

my machine. Fig. 13 a view thereof in longitudinal central section on the line *i—j* of 55 Fig. 12. Fig. 14 a view thereof in central cross section. Fig. 15 a broken view of the machine in central horizontal section of the right and left hand billet-receiving members, the die-holding member and the mandrel-holding member drawn to a larger scale 60 than the corresponding parts shown in Fig. 4 and showing the die and mandrel in operative positions, and the rams advanced for the extrusion of the billets of metal. 65

My invention relates to an improved machine for extruding metal tubes, rods and the like, the object being to produce a machine constructed with particular reference to increased capacity for work, reduction in 70 the amount of scrap, and ability to produce tubes and kindred forms of larger diameter and greater length than has heretofore been possible.

I may here state that my present invention 75 is an improvement upon, and represents an evolution of the disclosure of United States Patent No. 1,011,522 granted December 12, 1911, to the Chase Rolling Mill Company, on my application. 80

With these ends in view, my invention consists in a machine for extruding metal as will be hereinafter described and pointed out in the claims.

In carrying out my invention, I employ 85 a sectional container of separate power-operated parts in place of the solid container heretofore employed in machines of this character.

My improved sectional container consists, 90 as herein shown, of a left hand billet-receiving member 2, a corresponding right hand billet-receiving chamber 3, a die-holding member 4, and a corresponding mandrel-holding member 5. The billet-receiving 95 members 2 and 3 which have the members 4 and 5 interposed between them, are formed with heavy circumferential retaining-ribs 6 adapting them to be solidly mounted by heavy, exteriorly threaded annular nuts 7, 100 in recessed cross-heads 8 and 9 formed near their corners with large circular openings 10 for the reception of massive tie rods or columns 11 upon which the said cross-heads 8 and 9 ride back and forth in assembling 105 and disassembling the sectional container.

For reciprocation upon the tie-rods 11, the cross-head 8 is formed upon its upper and lower edges with integral lugs 12 located diagonally opposite each other on a line 5 passing through the center of the cross-head. These lugs 12 mount piston-rods 13 carrying pistons 14 operating in cylinders 15 fastened to the top and bottom of the main-casting 16 forming the core of the machine. 10 Water under pressure is admitted to the cylinders 15 through pipes 17 suitably connected therewith. The said cross-head 9 is formed with corresponding lugs 18 mounting piston-rods 19 carrying pistons 19 like 15 the pistons 14 aforesaid. The said piston-rods 19 operate in hydraulic cylinders 20 fastened to the top and bottom of the main casting 16 and having water under pressure admitted to them by means of suitable pipes 20 21. Under this construction and arrangement of parts the billet-receiving sections 2 and 3 of the sectional container are moved back and forth in line with each other, toward and away from the die-carrying section 25 4 and the mandrel-carrying section 5 of the container which sections are moved toward and away from each other in a line at a right angle to the alignment of the billet-receiving sections 2 and 3. 30 The die-holding container-section 4 is formed in its inner face with a centrally threaded recess 22 for the reception of a suitable die 23 the particular form of which will depend upon the character of the product to be extruded. At its outer end the section 4 is formed with a threaded recess 24 for the reception of the inner end of a hollow coupling-spindle 25 passing outward through a cross-head 26 and receiving upon 40 its projecting threaded outer end, a nut 27 by means of which the die-holding section 4 is firmly attached to the said cross-head 26 which is formed at its four corners with sockets 28 receiving four horizontally arranged tie-rods 29 the inner ends of which are supported upon the main-casting 16, and the outer ends of which are supported in a frame 30 mounting the hydraulic cylinders 31 employed for reciprocating the die-carrying section 4. The said die-carrying section 4 is also formed with a central discharge-passage 32 in line with the bore of the spindle 25 which latter opens into a discharge-pipe 33 the inner end of which is 50 threaded into a nut 27, and the outer end of which is supported in any suitable manner in a frame, it being understood that the extruded product, whether tubular or solid, is discharged from the machine through the 55 passage 32, the spindle 25 and the pipe 33. The hydraulic cylinders 31 contain pistons 34 carried by the outer piston rods 35, 35, the inner ends of which are mounted in the cross-head 26 as shown in Fig. 7, water 60 under pressure being admitted to, and with- 65

drawn from the cylinders 31 through pipes 36, whereby the cross-head 26 is reciprocated for moving the die-carrying member 4 of the container into and out of place.

The mandrel-carrying section 5 of the 70 container is formed in its inner face with a recess 37 having a concentric threaded counterbore for the reception of the mandrel 38 which will be conformed in character to the die 23. At its outer end the section 5 is 75 formed with a central threaded opening 39 for the reception of the threaded inner end of a hollow spindle 40, corresponding to the spindle 25 aforesaid, and passing outward through a cross-head 41 corresponding to 80 the cross-head 26. The spindle 40 connects the section 5 with the cross-head 41 in the same manner in which the spindle 25 connects the section 4 with the cross-head 26. As shown in Fig. 7, the section 5 is formed 85 with a central opening 42 for the cooling of the mandrel, if that is desired.

The cross-head 41 is formed upon its four corners with sockets 43 receiving four tie-rods 44 supported at their inner ends upon the main-casting 16 and entered at their outer ends into a frame 45 mounting two hydraulic cylinders 46 which correspond in every way to the cylinders 31 shown in Fig. 7. The cylinders 46 receive piston-rods 47 95 corresponding to the piston-rods 35. The cylinders 46 have water under pressure admitted to, and withdrawn from them through pipes 48 corresponding to the pipes 36 aforesaid. The cylinders 46 are thus employed for moving back and forth the cross-head 41 and hence the mandrel-carrying section 5 of the sectional container.

It will be understood from the foregoing that the billet-receiving container-sections 2 and 3 are advanced into the main-casting 16 and retracted therefrom in line with each other, and that similarly the die-receiving section 4 and the mandrel-receiving section 5 are advanced into the main-casting 16 and retracted therefrom in a line at a right angle to the line of movement of the billet-receiving container-sections 2 and 3. The timing of the advance and retraction of the container parts 2 and 3, and 4 and 5, will be described later on. After the said sections 2 and 3, and 4 and 5, of the sectional container have been hydraulically assembled, as described, in the main-casting 16, heated billets are introduced into the outer ends of the billet-receiving container sections 2 and 3 in any approved manner and by any approved mechanism. After the billets have been positioned, the metal contained in them is extruded by subjecting their outer ends to pressure by means of rams 49 and 50 which are simultaneously advanced from opposite directions under tremendous hydraulic power. As shown, the rams 49 and 50 are mounted at their outer ends in yokes 130

51 suspended at their upper ends from pins 52 in the cross-heads 53 and 54. The said cross-head 54 (Figs. 4 and 6) slides upon the heavy tie-rods 11 upon which it is moved 5 forwardly by means of a piston 55 bolted to its outer face and operating in a cylinder 56 to which water under pressure is admitted through a pipe 57 centrally applied to the outer end of the cylinder 56. For the 10 retraction of the cross-head 54, and hence of the ram 50, I employ four retracting-rods 58 connected at their inner ends with the cross-head 54, and at their outer ends with yokes 59 mounting the outer ends of two 15 piston-rods 60 operating in retracting-cylinders 61 mounted upon the outside of the cylinder 56 and having water under pressure admitted to them through pipes 62. The left-hand ram 49 corresponding to the 20 right hand ram 50 is mounted in a yoke 51 pivotally suspended in vertical position from the inner face of the said cross-head 53 which corresponds in all respects to the cross-head 54, and is operated in the same 25 way by means of connections which duplicate the connections of the cross-head 54 and which are, therefore, not shown in full detail, but which comprise a heavy cylinder 63 corresponding to the cylinder 56 and re- 30 ceiving a piston, not shown, but bolted to the cross-head 53 and operating to move the cross-head 53, and therefore the ram 49, inward upon the tie-rods 11 with great power. The cross-head 53, and hence the ram 49, 35 are retracted by means of four tie-rods 64 connected at their inner ends with the said cross-head and at their outer ends with a yoke 65 mounting two pistons 66 entering cylinders 67 corresponding to the cylinders 40 61 aforesaid. An inlet pipe 68 corresponding to the pipe 57 admits water to the cylinders 63.

For the purpose of retiring the rams 49 and 50 to provide free access to the outer 45 ends of the billet-receiving container sections 2 and 3, the said rams are mounted, as has already been described, in pivotal yokes 51. For the purpose of retiring the rams, they have operating links 69 connected with 50 them, and with any convenient source of power, none being shown. By applying power to the links 69, the yokes 51 will be swung into horizontal positions, as shown by broken lines in Fig. 6, causing the rams 55 to be swung through a quarter circle, leaving the space immediately adjacent to the outer ends of the containers 2 and 3 and in line with the bores thereof, clear for the free and convenient handling of the heated 60 billets.

As shown, I provide for the actual insertion of the heated billets into the container-sections 2 and 3, two small auxiliary-pistons 70 one of which is shown in Fig. 6. This 65 is mounted in the center of the cross-head

53 in line with the bore of the billet-receiving container section 3, and extends into a small cylinder 71 to which air under pressure is supplied by pipes 72, the said cylinders 71 being located centrally within the 70 piston 55 which is hollow. A heated billet temporarily supported in line with the bore of the container-section 3 is pushed into the same by the piston 70 when air is admitted through one of the pipes 72 into the pneumatic cylinder 71. Just as soon as the billet has been pushed by the piston 70 into the container-section 2, the piston 70 is withdrawn by the admission of air into the opposite end of the cylinder 71 after which the ram 49 is restored to its normal position through the medium of its power link 69. It will be understood, of course, that the piston within the cylinder 63 on the opposite side of the press also receives a pneumatic cylinder for the operation of a piston for pushing heated billets into the billet-receiving container-section 2 in the manner described.

In order that the rams 49 and 50 may be advanced at exactly the same speed, and that any tendency to depart from synchronism may be immediately corrected, I preferably, and as herein shown, employ two pairs of speed-controlling cylinders 73, 73, 75 and 74, 74, which are exact duplicates of each other. The cylinders 73, 73, are located on opposite sides of the cylinder 56 containing the piston 55 employed to operate the cross-head 54 carrying the ram 50, 100 while the cylinders 74, 74, are located on opposite sides of the cylinder 63 employed to operate the cross-head 53 carrying the ram 49. The two cylinders 73, 73, are furnished with pistons 75 mounted upon piston-rods 76 the forward ends of which are connected with the opposite sides of the cross-head 54 which thus serves to couple together the pistons 75 and the piston 55. Similarly the speed-controlling cylinders 105 74, 74, are furnished with pistons (not shown), but corresponding to the pistons 75 and mounted upon piston-rods 77 the inner ends of which are connected with opposite sides of the cross-head 53 which thus 110 serves to couple together the pistons upon the rods 77 with the piston within the cylinder 63. The outer ends of the speed-controlling cylinders 73, 73, are connected by pipes 78 with the inner ends of the speed-controlling cylinders 74, 74, while the outer ends of the said speed-controlling cylinders 74, 74, are connected by pipes 79 with the inner ends of the speed-controlling cylinders 73, 73. The pipes 78 and 79 are normally kept full of water which acts as a 115 solid connection between the said two pairs of speed-controlling cylinders and their pistons. Now as the pistons 75 are coupled with the main piston 55 through the cross-

head 53, and as the pistons of the rods 77 are coupled with the piston within the main cylinder 63 through the cross-head 53, the pistons 75 and their complementary pistons 5 on the piston-rods 77 must advance at exactly the speed of the main piston 55 and its complementary main-piston within the cylinder 63, which they cannot do unless the water displaced by the inward movement 10 of the pistons 75 is precisely equal in amount to the amount of water displaced by the inward movement of the complementary pistons of the piston rods 77, all of the speed-controlling cylinders and their 15 pistons and rods being of the same size. If, for any reason, one of the main rams 49 or 50 meets with less resistance than the other, the tendency will be for it to move faster than the other. This tendency, however, will be immediately checked and corrected for the reason that the ram 49 meeting with less resistance, cannot move faster than the water in the speed-controlling cylinders 73, 73, connected with it can be transferred 20 to the outer ends of the complementary speed-controlling cylinders 74, 74, and this cannot take place until the two speed-controlling cylinders 73 can be prepared to accommodate the excess of water 25 by the forward movement of their pistons 75. In other words, the water in the pipes 78 and 79 acts, as above stated, in effect as a solid body to transfer energy from the main ram moving too rapidly to the main 30 ram moving too slowly, whereby the ram moving too rapidly receiving an excessive load is thus checked in speed, while the other ram is accelerated in speed. In this way, when one ram tends to gain in speed, 35 the load is immediately put upon it which synchronizes it with the other ram, and vice versa.

In order to keep the pipes 78 and 79 at all times filled with water, I provide them 40 with water-supply check-valves 80 of any approved construction, which automatically open to permit the water to flow into the said pipes to make up for any loss by evaporation or leakage, and automatically close 45 to prevent any escape of water during the closing of the said apparatus. The said pipes are also provided with relief check-valves 81 opening outwardly, but normally held closed by a predetermined external 50 water pressure equivalent to a maximum water pressure above which it is designed that the pressure of water in the pipes 78 and 79 and in the cylinders 73 and 74 shall not be carried. In case the water pressure 55 in the said cylinders 73, 73, and 74, 74, and pipes 78, 79, passes this predetermined maximum pressure, the relief check-valves 81 automatically open outwardly and afford the desired relief.

65 The reason why it is highly important

that the main rams 49 and 50 shall advance at a uniform speed is, that it is desirable that the two billets in the billet-receiving container-sections 2 and 3 shall be extruded at uniform speeds so as to produce the highest 70 quality of extruded stock.

Having described my improved machine, I will now proceed to set forth the method of operating it in the production of extruded stock.

75 In the first place, the valves controlling the hydraulic cylinders operating the die and mandrel container-sections 4 and 5 are manipulated to cause the said sections to be advanced into their assembled positions in 80 the main-casting 16, as shown in Figs. 4 and 7. The valves controlling the cylinders 15 and 20 are now manipulated to cause the billet-receiving container-sections 2 and 3 to be advanced into position in the main-casting 16, the inner ends of the said container-sections 2 and 3 being at this time jammed home upon the opposite faces of the die and mandrel holding container-sections 4 and 5, which are thus solidly held in 85 place during the extrusion operation. The rams 49 and 50 are then swung into their clearance or billet-feeding positions. Heated billets are now introduced into the machine and held in alignment with the bores 90 of the billet-receiving container-sections 2 and 3, while the pneumatic valves controlling the auxiliary billet-inserting pistons 70 are operated to cause the same to advance 95 and push the billets into the said sections 100 2 and 3, as well as steel dummy blocks, so called, which follow the billets into the container during the extrusion process. The pistons 70 are now pneumatically retracted 105 into their retired positions after which the rams 49 and 50 are swung back into their operating positions as shown by full lines in Fig. 6. The valves admitting water back of 110 the main piston 55 and its complementary piston in the cylinder 63 are now manipulated to cause the said pistons to move inward with great power, whereby the respective rams are entered into the respective container-sections 2 and 3 causing the metal 115 of the billets to be extruded around the mandrel 38 through the die 23 and expelled from the machine through the passage 32, the spindle 25 and the discharge-pipe 33. When all of the metal forming the mass of both billets has been extruded, leaving merely a 120 small mass of unextruded metal around the mandrel, and the dummy blocks aforesaid, the rams 49 and 50 are then withdrawn from the container-sections 2 and 3, and moved into their retired positions by the 125 proper manipulation of the valves controlling the water pressures in the cylinders 56 and 63. The water pressures in the two pairs of cylinders 15 and 20 is then released 130 so as to relieve the die and mandrel-holding

sections 4 and 5 of the container from the clamping section of the billet-receiving sections 2 and 3 thereof, after which the water pressures in the pairs of cylinders 31 and 46 are used for the retraction of the container-sections 4 and 5, as shown in Fig. 5. During this operation, the stump or unextruded bit of metal, and both of the dummy blocks, will follow the die-holding container-section 4 to which they will be attached by the last end of the extruded tube, which will be contained within the section 4 from which the stump and dummy blocks must now be cut or broken away. In the ordinary operation of the machine it will not be necessary to systematically retract the billet-receiving container-sections 2 and 3 from the main-casting, since it will suffice, in ordinary practice, to move them inward just enough to clamp them upon the sections 4 and 5 after the same have been moved into position, and move them outward just enough to relieve the said sections 4 and 5 preparatory to the retraction thereof. However, the machine will at any time be in readiness for the retraction of the sections 2 and 3 into the position in which they are shown in Figs. 5 and 11 if for any cause whatever this shall seem either necessary or desirable. The cycle of operations above detailed is now repeated, and so on.

While my improved machine is primarily designed for the simultaneous extrusion of two billets of equal length, as already described, it is also adapted to be advantageously used as a single billet machine. In such use of the machine I may employ a cylindrical billet and pierce the same in the machine by means of the mandrel, or I may employ a special billet pierced prior to its introduction into the machine which may be used without alternation for the extrusion of single billets pierced as aforesaid prior to introduction into the machine, or thereafter.

In using the machine as a single billet machine, the container-sections 2 and 3, as well as the die-holding and mandrel-holding sections 4 and 5 will be moved into their retired positions as shown in Figs. 5 and 11, whereby the central portion of the main-casting will be left unoccupied. The single billet will then be introduced diagonally or otherwise maneuvered into the main casting 16 from one side or the other thereof, and then swung into alignment with the bores of the container-sections 2 and 3 which will then be advanced and sleeved over it, as it were. If the billet is a solid billet, the container-sections will be advanced toward each other nearly to the limit of their inward movement, but sufficiently short of the same to permit the die-holding section 4 to be first positioned, after which the mandrel-holding section

will be moved into the main-casting for action in conjunction with the die-holding section 4 to pierce the billet after which the container-sections 2 and 3 will have their inward stroke completed for clamping the die-holding and mandrel-supporting sections in place. In case the single billet has been pierced prior to its introduction into the machine, the method is the same except that the die-holding and mandrel-holding sections 4 and 5 of the container will be simultaneously, instead of successively, advanced. The advantage of using my improved machine as a single billet machine is, that it permits the use of single billets nearly as long as the total stroke of the two rams 49 and 50, and therefore substantially equal to the length of both billets when the machine is used as a double billet machine. There are some advantages attending the use of a single billet over two billets, particularly in connection with the subject of material, as some materials extrude better than others. In case the billet is pierced prior to its introduction into the machine, it may be otherwise than uniform in cross-sectional form, and may take some such shape as shown in Figs. 12, 13 and 14, in which the billet 81 has corresponding cylindrical ends and an enlarged perforated central portion 82.

I claim:

1. In an extrusion machine, the combination with a sectional container comprising several movable coöperative sections adapted to be assembled and disassembled, of means for moving the several sections of the container toward each other into their extrusion positions and away from each other in their clearance positions.

2. In an extrusion machine, the combination with a sectional container comprising two billet-receiving sections, a die-holding section, and a mandrel-holding section; and means for moving the said sections into their assembled and clearance positions.

3. In an extrusion machine, the combination with a skeleton main-casting having its opposite sides correspondingly recessed and formed with a transverse slot or opening, of a sectional container comprising billet-receiving sections and die-holding and mandrel-holding sections shaped to fit into the recessed and slotted main-casting.

4. In an extrusion machine, the combination with a main casting having recessed side faces, and a transverse opening, of a sectional container consisting of two billet-receiving sections entering the recessed side-openings of the casting, and a die-holding and a mandrel-holding section entering the transverse opening of the casting, and means for moving the several sections into their assembled and clearance positions.

5. In an extrusion machine, the combina-

tion with a skeleton main-casting having recessed sides, and a transverse opening or slot, of a sectional container comprising two billet-receiving sections, and a die-holding and mandrel-holding section, two cross-heads respectively fitting into the recessed sides of the main-casting and carrying the respective billet-receiving container-sections, means for operating the said cross-heads, 5 means for carrying and operating the said die-holding and mandrel-holding sections which enter the opposite ends of the transverse opening or slot in the main-casting, and pressure rams arranged in line with the 10 bores of the said billet-receiving container-sections.

6. In an extrusion machine, the combination with a main casting, of a sectional container comprising a plurality of 20 movable parts, means for moving the parts of the container into their assembled and clearance positions, and a hinged pressure ram adapted to be swung into a retired position for the introduction of a heated billet 25 into the container.

7. In an extrusion machine, the combination with a main casting, of a sectional container comprising two billet-receiving container-sections, means for synchronously 30 moving the said container-sections toward each other into their coöperation extrusion positions and away from each other into their stump-extrusion and charging positions, and two movable pressure rams adapted 35 to be retired for the introduction of heated billets into the respective billet-receiving container sections.

8. In an extrusion machine, the combination with a main casting, of a sectional container the parts of which are movable into 40

and out of the said casting, and including two billet-receiving container-sections, and two hinged pressure-rams adapted to be swung into retired positions for the introduction of heated billets into the respective 45 billet-receiving container-sections.

9. In an extrusion machine, the combination with a skeleton main casting, of a sectional container the parts of which are moved into and out of the said casting, two 50 pressure rams, cross-heads upon which the said rams are pivotally mounted, hydraulic pistons for operating the said cross-heads, and pistons located within the main pistons in line with the said rams for pushing heated billets into sections of the container when the rams are swung into retired positions.

10. In an extrusion machine, the combination with a skeleton main-casting, of a sectional container the parts of which are adapted to be assembled in the said casting and comprising two billet-receiving sections and a die-holding and a mandrel-holding section, two main rams, movable cross-heads with which the said rams are pivotally connected, main pistons for the operation of the said cross-heads and rams, and pneumatic pistons located within the main pistons in position to push the heated billets into the billet-receiving container-sections 65 when the rams are swung into their billet feeding positions.

In testimony whereof, I have signed this specification in the presence of two subscribing witnesses.

DAVID L. SUMMEY.
